UNITED STATES PATENT OFFICE

164,508

MULTIPLE LIGHTING FIXTURE

Clyde D. McCann, Des Moines, Iowa

Application November 10, 1947, Serial No. 142,426

Term of patent 14 years

(Cl. D48—23)

To all whom it may concern:

Be it known that I, Clyde D. McCann, a citizen of the United States, residing at Des Moines, in the county of Polk and State of Iowa, have invented a new, original, and ornamental Design for Multiple Lighting Fixture, of which the following is a specification, reference being had to the accompanying drawing, forming a part thereof, in which:

Fig. 1 is a perspective view, Fig. 2 is a plan view, and Fig. 3 is a side view of a multiple lighting fixture, showing my new design.

I claim:

The ornamental design for a multiple lighting fixture, substantially as shown.

CLYDE D. McCANN.
